UNITED STATES PATENT OFFICE

JOHN D. CRAFT, OF EVANSVILLE, INDIANA

REFRIGERATOR

Application filed June 6, 1927. Serial No. 196,689.

My invention relates to refrigerators and ice boxes, and particularly to the type having inner and outer doors.

While the use of inner and outer doors on refrigerators is not broadly new, it is the object of my invention to provide multiple units of inner doors of glass or other transparent material which are arranged to close off compartments independently of the outer door closure as far as size and shape is concerned. It is, however, an object of my invention to so arrange the inner doors that they will be closed when the outer doors are closed. This object I preferably accomplish by the disposition of members which are adapted to be abutted by the outer doors upon closure which will bear against the inner doors, and so insure their closure also. The arrangement of inner doors also has for its object the provision of means for preventing undue heating up of the entire refrigerator during the intervals when articles are being placed in or removed from the refrigerator. A further object is the construction of a refrigerator which will be free of external sweating due to a particular arrangement of gaskets and supporting strips.

The above and other objects which will be referred to during the ensuing disclosure I accomplish by that certain arrangement and combination of parts of which I have shown a preferred embodiment.

Referring to the drawings:

Figure 1 is a front elevation of a refrigerator showing my invention, in which the door to the food compartment on the right is shown in open position, and in which the middle one of the three glass doors is open.

Figure 2 is a sectional view of the refrigerator as it would appear taken along the lines 2-2 in Figure 1 with the outer door closed.

Figure 3 is a sectional view of the refrigerator as it would appear taken along the lines 3-3 in Figure 1 with both the outer door and the inner doors all closed.

Figure 4 is a sectional view of the refrigerator as it would appear taken along the lines 4-4 in Figure 1 with both inner doors and the outer door closed.

Figure 5 is a sectional view of the refrigerator as it would appear taken along the lines 5-5 in Figure 1, with both inner doors and the outer door closed.

The refrigerator shown is of the side icier type, and it has a casing 1 with front openings closed by the outer doors 2 which are hinged to the casing as indicated at 3. I have shown standard types of handles and latches at 4 with which the outer doors may be kept securely fastened. Within the casing and interspaced from the outer or storm doors I have shown a plurality of glass panels 5 which are hinged to the casing as indicated at 6. The glass panels may be whatever size and shape is most convenient. In the refrigerator shown, I have indicated a series of wire screens 7 which divide the box into food compartments. The glass panels are preferably so arranged that they coincide with the food compartments. For example, if it is desired to open up the top compartment only, the top panel may be used, and the coldest air in the box which will be in the lower portion, need not be disturbed. By placing those articles which are to be removed and used the more frequently in the upper compartments, much economy in preventing needless introduction of warm exterior air is avoided. The glass panels are interspaced from the outer door by what may be called a dead air space 8 which is another feature which makes for economy.

The glass panels when closed, bear against a resilient bumper rail 9 mounted against the jamb strip 9^a. The bumper serves to prevent such a great jarring strain during the closing of the door as to make fracture likely, and also to prevent radiation through the opening between the panel and the casing. The outer door also has a resilient bumper rail 10 which it abuts when closed, and in order to provide a simple and inexpensive device for supporting the bumper rails, I have provided an L-shaped metal strip 11, which supports both the bumper rails, and is insulated from the metal parts on the inside and outside of the box by the bumper rails. The construction of bumper support which I have shown prevents a direct metal contact

between the outer portion of the box and the inner portion, so that external sweating is substantially minimized.

Another feature of importance is the bumper device which I have shown clearly in Figure 4, which prevents any likelihood of closing the outer door in such a way as to fracture the inner door, and also insures that the inner doors will always be closed when the outer door is closed. I have shown openings 12 in the glass panels through which rods 13 are extended. The outer ends of the rods are enlarged and rounded as indicated at 14, so that they may serve as handles for the panels, and also as abutments which will have smooth bearings against the inner surfaces of the outer doors. Within the holes 12 I have shown supporting flanges, the inner flange being in the form of a lock nut 15, and the outer flange having a sleeve like body 16 which is threaded into the lock nut. The plunger rods 13 extend through the sleeve in which it has a slidable bearing. A nut 17 on the end of the shaft limits the outer extension of the plunger by its engagement with the nut 15. A spring 18 on the outer side of the panel bears outwardly against the enlarged ends 14 of the rods 13. I prefer to make the rods of sufficient length so that when the door is actually open enough to have broken the air seal within the dead air space, the plunger rods will still be in engagement with the inner surfaces of the doors, so that there will be no tendency for a suction effect to be created, which will tend to make the glass panels swing open when the outer doors are open. Thus, I can normally avoid the use of any types of catch or lock on the inner doors, as there will be no tendency for an inner door to swing open unless it is manually opened by the use of the handle 14.

Having thus described my invention what I claim as new and desire to secure by Letters Patent is:—

1. In combination with a casing having a refrigerating enclosure, means subdividing the refrigerating enclosure into a plurality of compartment doors forming closures for the compartments, and said casing having an opening through which all of said compartments may be exposed, and a closure for said opening independent of the compartment closures, and resilient means carried by the compartment doors adapted to be engaged by the opening closure substantially at its closed position whereby closing of the closure will close the compartment doors.

2. In a refrigerator an inner closure for a compartment, and an outer closure with an air space between the closures, and resilient means engageable at substantially closed position of the outer closure for insuring the closure of the inner closure.

3. In a refrigerator an inner closure for a compartment, and an outer closure with an

air space between the closures, and means engageable at substantially closed position of the outer closure for insuring the closure of the inner closure, said means so arranged as to bear against the inner closure and keep said inner closure closed until the outer closure has been opened sufficiently as to avoid the effect of suction formed in the air space with the initial opening of the outer closure.
